J. S. Jewett and J. H. Smith
Design for a Wood Stove
Patented January 25th 1853.

Des. 541

Sherman S. Jewett, and
Francis H. Root, of Buffalo, N.Y.
Letters Patent No 541. Dated Jan 25th 1853,

The schedule referred to in these Letters Patent and making part of the same

To all whom it may concern:

Be it known that we, S. S. Jewett and F. H. Root, of Buffalo, in the County of Erie, and State of New York, have invented or

produced a new and ornamental design for Wood Stoves, of which the following, is a full, clear and exact description, reference being had to the accompanying drawings which form part of this specification and which represents the several ornaments on the door, side and bottom plates, constituting our newly invented design.

The stove is of an oblong form, having a hearth or gender in front. The side plates (S) of the stove are embellished with parallelogramic mouldings surrounding a fanciful device, in alto relieve, consisting of a centre ornament (A) resembling an inverted heart with scroll projections (a), and a leaf (b) at the bottom, and floral branches (B) extending from either side bearing fruit (c). The front plate (C) of the stove is of architectural design, having, on either side of vertical oblong mouldings, rounded columns or pillars (d), the door hinged to this plate consists of a fascia (e) at the top surmounting a cavetto (f), with an ovolو moulding (g) on the face, the lower portion of the said oblong ovolو moulding being extended over the lower part of the front plate (C) and within the said ovolو moulding (g) is a vertical parallelogramic panel bordered by a moulding (h) and containing a central ornament formed of four adjoining leaves (i) with a semi-sphere in their centre and a semi-oblato-spheroid above and below them, from either of the two latter a floral plume (J) projects, carrying at its central extremity a projection (k) resembling the cone of the fir tree.

The bottom plate (E) of the stove is embellished with a border surrounding the side and end plates of the stove at their base; the ornaments constituting the said border consist of devices (L) resembling shields, separated by anchor formed ornaments (Y), fast to this bottom plate, and projecting in front of the stove is a spreading hearth (G) the sides of which are mounted with projecting, curved, grooved, and rounded stems (m), terminating in volutes or scrolls (n) at their inner ends and united at their front extremities with an enriched continuation or front border embellished as represented in the drawings consisting of a centre group ornament (I) with leaf or scroll branches (J) jutting from either side of the ornament I, to the stems m.

Having thus described our ornamental design for Wood Stoves, what we claim as new therein and desire to secure by Letters Patent, is the configuration and arrangement of the ornamental device on the side plates of the stove, as represented and described.

Des. 541

We also claim the ornamental design of the fire door as represented and described:

We likewise claim the ornamental configuration of the bottom plate (F) as described.

In testimony whereof we have hereunto subscribed our names,
